LOUIS JENSEN
By Frank D. Thompson
Atty. for

UNITED STATES PATENT OFFICE.

LOUIS JENSEN, OF CHICAGO, ILLINOIS, ASSIGNOR TO UNITED AUTOGRAPHIC REGISTER CO., OF CHICAGO, ILLINOIS, A CORPORATION OF ILLINOIS.

PAPER-FEEDING MECHANISM FOR TYPEWRITING MACHINES.

Application filed June 3, 1921. Serial No. 474,328.

To all whom it may concern:

Be it known that I, LOUIS JENSEN, a citizen of the United States, residing at Chicago, in the county of Cook and State of Illinois, have invented certain new and useful Improvements in Paper-Feeding Mechanism for Typewriting Machines, of which the following is a full, clear, and exact description.

10 My invention relates to improvements in typewriting machines and particularly to means for feeding continuous strips of paper therefrom, step by step.

15 The object of my invention is to provide mechanism which can be attached to the carrier of either a new or an old typewriting machine to withdraw therefrom step by step sections of a continuous strip of paper, of predetermined lengths which usually have 20 the same forms printed upon them and are provided with series of correspondingly located equi-distant postholes near the tops of or advanced edges of the said printed forms.

25 This I accomplish by the means herein-after fully described and as illustrated in the drawings in which corresponding parts are indicated by the same reference numerals.

30 In the drawings:

Figure 1 is a side elevation of the upper portion of the supporting-frame of a typewriting machine, and an end view of the carrier, with the support for the ribbon-wheels broken away, and with my improvements applied thereto.

Figure 2 is a plan view of approximately one half of the same.

40 Figure 3 is a front elevation of the carrier removed from its support, and with my improvements applied thereto.

Figure 4 is a vertical transverse section taken on dotted line 4, 4, Figure 2, looking in the direction indicated by the arrows.

45 Referring to the drawings, 5 represents the supporting-frame of my invention which is constructed and designed in any suitable manner to support the carrier so that it can reciprocate back and forth, and accommodate 50 and support the type-letters and keys for operating the same (which are not shown), all contained in any of the well-known typewriting machines.

The carrier to which my improvements are attached may be constructed similar to 55 the carriers of any of the type-writing machines now in extensive use, but, for the purpose of describing my invention the carrier of the typewriting machine, which I have selected is, as shown in the 60 drawings, and is provided with end-frames 6, 6, the forward portions of which are connected by a cross-bar 7. This cross-bar has a longitudinal groove or runway in its upper surface, in which bearing-balls, 8, are placed 65 that are supported by and run in a similar runway 9, in a suitable track attached to the supporting-frame 5. The body of these end-frames extend to the rear of cross-bar 7, a suitable distance, and have arms 10 projecting from their upper rear portions, and these arms have the ends 11 of rearwardly extending brackets 12 securely fastened thereto that have bearings in their rear ends for the rear ends of the parallel legs 13 of a feed- 75 frame the forward ends of which latter are bent toward each other, as shown in Figure 3, and connected by a transverse member or head 14, substantially as shown in the drawings.

80 The rear end of one of the legs 13 of said extracting frame, (preferably the right hand leg), is provided with downwardly extending branch 15, and the lower end of this branch is connected to the adjacent leg by 85 a segmental rack 16, the curvature of which is struck from the pivotal center of said leg.

The head 14 consists of a flat transverse strip of metal whose ends are bent rearwardly and attached to the legs 13 in any 90 suitable manner, and is provided with holes or perforations 17, that are separated a distance corresponding to the distance between each pair of postholes, which, as hereinbefore stated, are located near the top of each 95 of the printed forms of the continuous strips of paper.

Near each end head 14 has the ends of leaf-springs 18 attached to its rear surface adjacent to its ends and these springs as they 100 extend toward the center of said head separate slightly therefrom and immediately back of the holes 17 are provided with forwardly projecting pins 19, 19, that extend through said holes.

105 The opposed free ends of the springs pro-

ject beyond these pins and their extremities 20 are grooved longitudinally to convex their forward surfaces.

In operation the extracting-frame is designed to be moved downwards and as it approaches the limit of its downward movement pins 19 engage and ride back of the upper edge of the strip or strips of paper and enter the postholes in the advanced 10 edges of the printed forms that are in position to be printed upon. This action of the pins is caused by reason of the extremities 20 of springs 18, engaging the rear transversely corrugated cam surfaces 21, 21, of 15 vertically disposed rectangular plates 22, whose lower ends are securely attached to the rear of a platen 23, which latter extends longitudinally and has its ends attached to the end-frame 6, 6, of the carrier. The cam surfaces 21 are of such proportions that when the pins 19 enter the postholes of the paper they will not, when the feeding-frames move upwards, cause the pins to withdraw entirely from said holes, and, thus, 20 the said paper will be extracted, step by step, as said frame moves upward.

The platen, is preferably, rectangular in cross-section and at its ends has Z-shaped brackets 24, 24, secured thereto, at points 30 about in the same vertical transverse plane as the ends of head 14. A transverse horizontally disposed flat metal strip or plate, 25, is secured to and supported by said brackets. This plate 25 is so positioned that 35 its flat side is vertical and it has a companion plate 26 arranged parallel in front of it, that is spaced apart therefrom by the interposition of spacing-blocks between the ends thereof to provide a discharge passage 40 through which the paper passes as it is extracted. These plates 25 and 26 are provided with vertically elongated slots 27, that are separated the same distance apart as the holes 17, 17, in head 14 and are located in 45 front of the same when the feeding frame is at the lowest limit of its movement.

The continuous paper strips, *a*, *b*, and *c*, are threaded through the machine by being passed over the pivotal rock-shaft 28, whose 50 ends are secured in the rear ends of brackets 12, and then extend forward down under the platen and then up in front of the platen and through the discharge passage between the plates 25 and 26. The upper edge of the 55 outer plate 25 of the discharge passage is, say, an inch above the platen, and when the feeding frame is approaching the lower limits of its movement, the free end of springs 18 will be drawn to the rear by the 60 engagement of their extremities and of the cam surfaces 21 and the forward ends of pins 19 will pass back of the advanced edges of the form next to be printed upon, and will then when said pins are axially in line 65 with the elongated perforations 27 have

reached the apex of the upper cam surface 21, will ride down the lower inclined portion of said cam and permits said pins to move through the perforations 27 and into the postholes of the paper strips.

The ends of the rock-shaft 28 extends through the legs 13 of the feeding-frame, and a V-shaped-frame 29 that is loosely journaled thereon and is retained in position by a screw 30 tapped longitudinally 70 into the extremity of said shaft. The length of the legs of said V-shaped frame is greater than the radius of the segmental rack 16, and the end of the uppermost of these legs has a pawl 31 pivoted thereto by means of a transverse pin 32. This pawl is kept in constant engagement with the teeth of said rack by means of a coil contraction spring 33, one end of which latter is secured to the pawl and the other to the leg of the 80 V-shaped frame, substantially as shown in Figure 1 of the drawings.

The end of the spring 33, is connected to pawl 31 through the medium of a transverse pin 34, and said pawl is connected by means 90 of a rearwardly extending rod 35, to an arm 36, loose on shaft 28 on the inside of the adjacent arm 12, and this arm has the rear end of a reciprocal bar 37 pivotally connected thereto, preferably, by the same 95 pivotal pin by means of which rod 35 is pivoted to said arm. This bar 37 extends forward alongside of the adjacent leg 13 of the feeding frame, and where the said leg is bent sidewise, passes under the same, 100 substantially as shown in Figure 3 of the drawings, and laps against the parallel surface of a hanger 38. The end of bar 37 coming in contact with hanger 38 is provided with a longitudinal slot 39, and it is 105 retained in engagement with said hanger by means of a screw 40 that passes through said slot and is tapped into said hanger so as to permit the longitudinal movement of the bar. The forward edge of the hanger 110 38 is flanged laterally to provide a thumb-grasp 41 and so likewise is the forward end of bar 37 to form a purchase for the fingers of the operator.

The outer end of the lower leg of the V- 115 shaped frame 29, has the rear end of a reciprocal rod 43 pivotally connected thereto by means of a crank-pin 44, and this rod extends forward to one of the arms 45, of a T-shaped lever 46, and is pivoted thereto. 120 This lever is fulcrumed at its angle to the platform 47 of a bracket 48 secured to and projecting laterally therefrom. The longer outer end of this lever 46 is shaped so that it can be conveniently grasped and moved 125 forward, so as to cause the V-frame 29, to rock and the pawl 31 to engage rack 16, and move it and the feeding frame upwards.

The feeding frame is maintained in its raised position by means of a braking-de- 130

vice consisting of a roller 49 which latter is pivoted to a spring-actuated arm 50 and this arm is pivoted to the portion of bracket 12, that depends from its lower edge to a 5 point below where said bracket is attached to arm 11 of the end-frame 6 just beyond the toothed edge of the rack. Arm 50 has an extension 51 depending below its pivot. The distance the feeding frame can be 10 moved upwards is determined by the gage 52, consisting of a U-shaped clip which is adjustable longitudinally on, and can be clamped to the segmental member of rack 16 in any position desired and limit the 15 downward movement of the rack and feeding frame.

What I claim as new is:

1. In a typewriting machine, the combination with the carrier, and a platen supported thereby, of a vertically reciprocal paper feeder consisting of a U-shaped frame the ends of which are pivotally connected to said carrier at the rear of said platen, and means that intermittently move said 20 feeder during the feeding operation, springs secured to the rear of the transverse bar of said frame, and pins secured to said springs, and extending through openings in and projecting forward beyond said bar 25 that engage postholes in the advanced portion of the paper after it has passed the platen.

2. In a typewriting machine, the combination with the carrier, and a platen supported thereby, of a vertically reciprocal paper feeder consisting of a U-shaped frame the ends of which are pivotally connected to said carrier at the rear of said platen, and means that intermittently move said 30 feeder during the feeding operation, springs secured to the rear of the transverse bar of said frame, pins secured to said springs, and extending through openings in and projecting forward beyond said bar that engage postholes in the advanced portion of 35 the paper after it has passed the platen and means that engage said springs when the frame is near the lower limits of its movement and draw said pins rearward and then 40 release and permit them to move forward.

3. In a typewriting machine, the combination with the carrier, and a platen supported thereby, of a vertically reciprocal paper feeder consisting of a U-shaped frame 45 the ends of which are pivotally connected to said carrier at the rear of said platen, a segmental rack secured to and depending from one of the legs of said frame whose curvature is struck from the axis of the same, and 50 means including a pawl that engages said rack and intermittently moves said frame upwards.

4. In a typewriting machine, the combination with the carrier, and a platen supported thereby, of a vertically reciprocal

paper feeder consisting of a U-shaped frame the ends of which are pivotally connected to said carrier at the rear of said platen, a segmental rack secured to and depending from one of the legs of said frame whose curvature is struck from the axis of the same, an oscillatory U-shaped frame the axis of which alines with that of said U-frame, a pawl pivotally connected to the end of one of the arms of said U-frame that engage said rack 70 and means for oscillating the same.

5. In a typewriting machine, the combination with the carrier, and a platen supported thereby, of a vertically reciprocal paper feeder consisting of a U-shaped frame 80 the ends of which are pivotally connected to said carrier at the rear of said platen, a segmental rack secured to and depending from one of the legs of said frame whose curvature is struck from the axis of the same, an oscillatory U-shaped frame the axis of which alines with that of said U-frame, a pawl pivotally connected to the end of one of the arms of said U-frame that engages 85 said rack, means for oscillating the same, 90 and a stop device secured to said segment and adapted to engage the upper arm of said U-shaped frame and limit the upward movement thereof.

6. In a typewriting machine, the combination with the carrier, and a platen supported thereby, of a vertically reciprocal paper feeder consisting of a U-shaped frame the ends of which are pivotally connected to said carrier at the rear of said platen, a segmental rack secured to and depending from one of the legs of said frame whose curvature is struck from the axis of the same, an oscillatory U-frame, the axis of which alines with that of said U-frame, a pawl pivotally connected to one of the arms of said U-frame that constantly presses toward and engages said rack, and means for disengaging said pawl when said feeder is moved downwards.

7. In a typewriting machine, the combination with the carrier, and a platen supported thereby, of a vertically reciprocal paper feeder consisting of a U-shaped frame the ends of which are pivotally connected to 115 said carrier at the rear of said platen, a segmental rack secured to and depending from one of the legs of said frame whose curvature is struck from the axis of the same, an oscillatory U-frame, the axis of which alines 120 with that of said U-frame, a pawl pivotally connected to one of the arms of said U-frame that constantly presses toward and engages said rack, an arm projecting downwards from the axial support of said U-frame a 125 manually operated reciprocal bar for moving said arm, and a rod connecting said arm to said pawl.

8. In a typewriting machine, the combination with the carrier, and a platen sup-

- ported thereby of a vertically reciprocal paper feeder consisting of a U-shaped frame the ends of which are pivotally connected to said carrier at the rear of said platen, a segmental rack secured to and depending from one of the legs of said frame whose curvature is struck from the axis of the same, an oscillatory U-shaped frame, the axis of which alines with that of said U-frame, a pawl pivotally connected to one of the arms of said U-frame a spring connecting said pawl to the arm of the U-frame to which it is attached, and means for disengaging said pawl when said feeder is moved downwards.
9. In a typewriting machine, the combination with the carrier, and a platen supported thereby, of a vertically reciprocal paper feeder consisting of a U-shaped frame the ends of which are pivotally connected to
- said carrier at the rear of said platen, a segmental rack secured to and depending from one of the legs of said frame whose curvature is struck from the axis of the same, an oscillatory U-shaped frame, the axis of which alines with that of said U-frame, a pawl pivotally connected to the end of one of the arms of said U-frame that engages said rack, a rod pivotally secured at one end to the other arm of the U-frame and a manually operated T shaped lever to one of the alining branches of which the other end of said rod is connected.
- In witness whereof I have hereunto set my hand this 7th day of May, 1921.
- LOUIS JENSEN.
